UNITED STATES PATENT OFFICE.

GEORGE E. MARLATT, OF PASADENA, CALIFORNIA.

TYPE-CASTING MECHANISM FOR LINOTYPE-MACHINES.

1,249,158.

Specification of Letters Patent.

Patented Dec. 4, 1917.

Application filed September 21, 1915. Serial No. 52,955.

To all whom it may concern:

Be it known that I, GEORGE E. MARLATT, a citizen of the United States, residing at Pasadena, in the county of Los Angeles and 5 State of California, have invented a new and useful Type-Casting Mechanism for Linotype-Machines, of which the following is a specification.

My invention relates to slug casting mechanism for typographical machines and particularly to a device insertible in the casting slot of the mold for regulating the length of the type slugs. My improved device is adapted to be used in connection with the 15 usual liner plates which are movable in the mold slot for forming ends for the slot, said liner plates being of different lengths and different liners being used for different lengths of slugs. With the improvements 20 hereinafter set forth in detail, it will be possible to produce type slugs of variable length, the liners being set to correspond to any desired length of slug thereby. Other 25 objects may appear as the description progresses.

Referring to the drawings, Figure 1 is a plan of the mold showing my liner placer instrument in position therein; Fig. 2 is a sectional elevation of the same on the line 30 2-2; Fig. 3 is a sectional elevation on the line 3-3; Fig. 4 is a partial front elevation; Fig. 5 is a fragmentary section of Fig. 1 on the line 5-5; Fig. 6 is a perspective view of the locking wire; Fig. 7 is an end elevation of Fig. 1 detached from the mold; Fig. 8 is a perspective view of the liner plate; and Fig. 9 is a perspective view of the mold cap. Similar characters of reference are 35 used in the specifications and the several 40 views of the drawing for indicating the same parts.

The liner placer instrument comprises an index bar 1 having a stationary head 2 secured thereto consisting of a top plate 45 with outwardly projecting arms 3 and 4 formed thereon and the end piece 5 provided with a recess 6 on the inner side in which a plug 7 is pivoted and a spring 8 is held for action against the plug. The plate is secured 50 to the bar 1 by means of screws 9 and the top of the bar 1 has a plurality of rectangular grooves 15 formed therein and numbered from 1 to 30 inclusive, the numerals representing ends of length and corresponding

with the scale on the assembler slide of the 55 machine.

A lock 10 is slidably held on the bar 1 and has a top plate 11 which is held by means of screws 12 on the body 13 and has grooves 14 formed on its upper surface, 60 these grooves being arranged in pairs and register with the grooves 15 on the bar 1, and are so spaced that one pair will register 65 ems and the other pair half ems. A plunger pin 16 is carried by the forward end of the 65 body 13 and is provided with the enlarged head 17' which is slidable in the body bore 17, the stem 18 being slidable in the smaller bore 19 and the outer end of the stem 18 being secured to the head 20. A spring 21 70 is carried on the stem 18 of the plunger and is compressible between the bottom of the bore 17 and the head 17' of the plunger for holding the head 20 normally against the body 13. The head 20 may be moved outwardly from the body 13 by compressing the 75 spring when the plunger is moved through the body.

A double pronged locking wire 22 slidably engages the grooves 14 of the body and 80 those 15 of the bar 1 for holding the lock 10 in any desired position on the index bar 1. The outer ends of the grooves 14 are slightly 85 countersunk so as to provide shoulders 23 therein, and the ends of the wire 22 are provided with shoulders 24 which are formed by notching the ends of the wire, so that when the wire 22 is pulled forward the shoulders 24 on the wire will engage those in the 90 grooves and ordinarily prevent the wire from being withdrawn from the body.

The plate 11 of the lock 10 has an extended arm 25 which is provided with a notch and shoulder 26, of a shape to conform to the edge of the liner 27, as shown in Fig. 1, the liner being pressed into position in the lock 10 between the arm 25 of the plate 11 and the plunger head 20, and thus held by the tension of the spring 21. The right hand liner 27' which engages the arm 3 of the head 2 serves for establishing the position of the instrument in the mold, and the plug 7 is held by means of the spring 8 against the end of the mold 28. The arm 3 is thus also resiliently held in contact with the liner 27'. 105

The mold 28 is of the ordinary type and consists of a base 28' and a cap 29, the cap having the rib cells 29' formed on its lower

surface. The pins 30 and 31 serve to hold the mold base and cap in alignment. The plate 32 which has a notch 33 formed thereon at one end for engagement with the pin 30 of the mold and the notch 34 at the other end for engagement with the pin 31, provides a casting surface different from that of the mold cap 29, under which it may be used.

10 In operation, this instrument, when inserted in the casting slot of the mold, as shown in Fig. 1, either with or without the plate 32, and the lock 10 set in a desired position, on the index bar 1 to correspond to the 15 length of the type slugs produced, serves as a positive means for effecting the placement of the liners 27 and 27' to correspond to the scale on the index bar. When the liners have been set in the proper places the instrument 20 may then be withdrawn from the mold. The space in the mold to the left of the liner 27 may be filled with type metal in the casting operation after the liners have been placed and secured in the usual manner, and 25 the type slugs are then cast in the space between the liners 27 and 27'.

The liner 27 provides a greater range of adjustment than is possible with usual form and the pin 35 ordinarily prevents the liner 30 from being placed with reference to the last few graduations of measurement indicated on the scale, and a groove 37 is therefore provided on the lower surface of the liner so that the liner may clear the pin 35 on 35 the mold. This groove as shown in broken lines in Fig. 1, also serves to receive the cast lines of metal which flows therefrom into the opening 38, unites with the liner, and thus firmly establishes the position of the liner 40 in the mold.

Having thus described my invention, what I claim is:—

1. A liner placer for typographical molds comprising a line measuring scale capable 45 of being held at one end in contact with the stationary liner provided with means adjustable to varying distances from said end for holding and regulating a placement of the movable liner whereby to fix the space 50 between the liners so as to conform to the desired lengths of the slugs produced thereby.

2. A typographical machine liner placer comprising an index bar having a scale 55 formed thereon, means on said index for engagement with a stationary mold liner, and adjustable means for supporting the movable liner and for setting said liner at desired points to produce type slugs of variable length.

3. A typographical machine liner placer comprising an index member provided with a suitable scale for measuring the length of the type slugs, and having a range conforming to the maximum length of said slugs,

and liner engaging and supporting means carried by said index member for effecting and regulating the placement of the mold liners for producing type slugs of variable length.

4. A typographical machine liner placer comprising an index member having a scale thereon with a range equal to the maximum length of the type slugs, and means movable relative to said index member and adapted to support the movable liner for regulating the placement thereof, relative to the stationary liner for producing type slugs of different length to conform to the length of the line to be printed.

5. A typographical machine liner placer comprising an index member having a scale for regulating the placement of the mold liners, and provided with a movable head for adjusting the movable liner, and a stationary head on said index member for engagement with the stationary liner, for regulating the length of the slugs.

6. A typographical machine mold liner placer having an index member provided with a range of movement corresponding to the maximum length of the matrix line, a head movably held thereon for adjusting the movable liner, and means for supporting the said index member in resilient engagement with the stationary liner for adjusting the position of said head and the spacing of said liners to correspond to a given length of type slug to be produced.

7. A typographical machine mold liner 100 placer comprising an index member having a scale thereon with a range equal to the maximum length of the type slugs to be produced, a stationary head on one end of said index for engagement with the stationary liner, a movable head capable of holding the movable liner for adjustment therewith attached to the opposite end of said index, and means for locking said movable head on said index member at a desired point for determining the length of the type slugs to be produced.

8. A typographical machine mold liner placer comprising an index bar, a stationary head on one end thereof having means for engaging the stationary liner, a movable head on the other end having means for engaging the opposite sides of the movable liner, and means for locking said movable head to said index bar for spacing said liners to correspond with the length of slugs to be cast.

9. A typographical machine mold liner placer comprising an index bar greater in length than the maximum length of the type slugs and provided with a stationary, and a movable head, said heads having means for resiliently engaging the stationary and movable liners, respectively, and means for locking said movable head at desired posi-

tions on said bar, for spacing said liners to correspond to the length of type slugs to be produced.

10. A typographical machine mold liner placer comprising an index bar having notches thereon corresponding to the units of measurement of the type slugs, a stationary head on and for holding said bar stationary relative to the stationary liner, and a movable head on and having means engaging the notches on said bar and adapted to engage and move the movable liner for spacing said liners to correspond to the length of type slugs to be produced.

15. 11. A typographical machine mold liner placer comprising a stationary and a movable head for engagement respectively, with the stationary and movable liners, and an index member connecting said heads and having notches formed thereon to correspond to ems of type measurement, and means on said movable head for engagement with the notches on and for locking said

head to said index bar at points corresponding to ems and half ems of measurement, 25 for regulating the length of type slugs to be produced.

12. A typographical mold liner placer comprising an index member having a plurality of transverse grooves formed thereon 30 at points corresponding to ems of measurement, a stationary and a movable head thereon having means for resiliently engaging the stationary and movable liners, respectively, and means on said movable head for 35 regulating the spacing of said liners to correspond to ems and half ems of measurement.

Signed at Los Angeles, in the county of Los Angeles, and State of California, this 40
23d day of August, 1915.
